UNITED STATES PATENT OFFICE.

EDWARD B. LEVERICH, OF NEW YORK, N. Y.

WASHING-MACHINE.

SPECIFICATION forming part of Letters Patent No. 398,170, dated February 19, 1889.

Application filed March 8, 1888. Serial No. 266,526. (No model.)

To all whom it may concern.

Be it known that I, EDWARD B. LEVERICH, a citizen of the United States, residing at New York, in the county and State of New 5 York, have invented new and useful Improvements in Washing-Machines, of which the following is a specification.

This invention relates to an improved washing-machine which is capable of accurate 10 adjustment as may be required by the articles being washed, as set forth in the following specification and claims, and illustrated in the accompanying drawings, in which—

Figure 1 is a sectional side elevation of a 15 washing-machine in the plane $x-x$, Fig. 2. Fig. 2 is a section in the plane $y-y$, Fig. 1. Fig. 3 is a section in the plane $z-z$, Fig. 2. Fig. 4 is a section similar to Fig. 3, showing a modification. Fig. 5 is a section similar to 20 Fig. 3, of another modification. Fig. 6 is a section in the plane $w-w$, Fig. 5. Fig. 7 is a plan view, partly in section, of a roller.

Similar letters indicate corresponding parts.

In the drawings, the letter A indicates a 25 tub or vessel having frames B, made to support rollers C. By making the frames B of metal said frames will not warp and will be strong and durable. The rubber D is connected to a frame, E, by means of a pivot or 30 pivots, F, and one or more nuts or set-screws, H, secured to the frame E and passing through a slot or slots in the arm or arms G of the rubber. By loosening the screw H the rubber D can be adjusted about the pivot F at any 35 desired angle, and fixed in a suitable position by tightening the screw H.

The frame E can oscillate about the pivot or rod I, connecting the frame E and the swinging arms J. Said arms J are supported 40 by a bar, K, resting by its ends in vertical slots in the upper ends of the uprights L. The bar K has a certain amount of vertical motion in the slots in the uprights L, and a spring or springs, M, press the bar K toward 45 the bottom of the tub A.

A vertical guide-pin, N, is provided for each spring M. In Fig. 3 the bar K is arranged to slide or move on the guide N while said guide remains stationary. In Fig. 4 the 50 bar K and guide N are arranged to slide together in ways in the uprights L. In Figs. 5

and 6 the bar C is supported in journals or boxes in the guides N. The spring M allows the space between the rubber D and rollers C to be increased or diminished, as required 55 by the greater or less amount of material inserted between the rollers and the rubber. When the parts are in position for operation, the rubber can be actuated by the handle O.

In addition to the oscillation which the rubber D can partake of in consequence of the arms J oscillating with the bar K or about the bar K, said rubber can oscillate with the frame E about the pivot I, and a stop 60 or stops, P, prevent excessive oscillation in one direction about the pivot I. As seen in Fig. 7, the rollers C are provided with pins Q and caps R of durable material—such as metal—said pins serving to support the rollers in the 65 frames B, and said caps preserving the rollers against being split, chipped, or injured.

What I claim as new, and desire to secure by Letters Patent, is—

1. The combination, with the uprights L, 70 having slotted upper ends, the vertically movable spring-pressed horizontal bar K, having its ends arranged in the slots, the swinging arms J, suspended upon the bar, and the frame E, pivoted to the lower ends of the swinging 75 arms, of the rubber D, pivoted at one side to the lower end of the pivoted frame and provided at its opposite side with upwardly-projecting arms G, adjustably secured to the pivoted frame, substantially as described. 80

2. The combination, with the tub A, having the attached frames B, and the rollers C, mounted in said frames, of the uprights L, the swinging arms J, the frame E, suspended from the swinging arms, the rubber D, pivoted at one side to the frame and provided at the other side with upwardly-projecting arms G, having curved slots, and screws H, adjustably connecting the slotted arms with the suspended frame, substantially as described. 85

In testimony whereof I have hereunto set my hand and seal in the presence of two subscribing witnesses.

EDW. B. LEVERICH. [L. S.]
